UNITED STATES PATENT OFFICE.

ERNEST C. KIRKPATRICK, OF SEATTLE, WASHINGTON.

WINDOW LOCK.

Application filed November 20, 1923. Serial No. 675,818.

To all whom it may concern:

Be it known that I, ERNEST C. KIRKPATRICK, a citizen of the United States, and a resident of Seattle, in the county of King and the State of Washington, have invented certain new and useful Improvements in Window Locks, of which the following is a specification.

My invention relates to improvements in window sash locks and an object of my invention is to provide a window sash lock of strong and simple construction that is neat in appearance and that will operate efficiently to lock a window sash either in a closed or an open position.

Another object is to provide a window sash lock that is easy to apply to a window sash and that will make it possible to dispense with the catch means ordinarily used for fastening the two sash of a window together.

A further object is to provide a window sash lock that will automatically snap into a locked position when the window is opened or closed and to provide a lock that is operated by a key or by such other means as to render it impossible to tamper with the lock from the outside of the window.

A still further object is to provide a lock of neat and ornamental appearance having a housing that may be made from a single piece of sheet metal stamped and bent to the desired shape to form a tubular bolt guide having a base arranged to rest on the top of a window sash and an end plate arranged to fit against and be secured to the side of said window sash.

Other and more specific objects will be apparent from the following description taken in connection with the accompanying drawings.

In the drawings Figure 1 is a fragmentary view in perspective of a window sash showing my invention installed thereon.

Fig. 2 is a plan view of a window sash lock constructed in accordance with my invention showing a key in the lock.

Fig. 3 is a view in side elevation of the same.

Fig. 4 is a longitudinal sectional view of the same showing the bolt withdrawn and showing the socket into which the bolt is adapted to project.

Fig. 5 is a view in cross section on broken line 5—5 of Fig. 4.

Fig. 6 is a detached view in perspective of a key that may be used in retracting the bolt.

Fig. 7 is a fragmentary sectional view showing one form of bolt socket that may be used in connection with the invention.

Fig. 8 is a perspective view showing a different form of bolt socket that may be used.

Fig. 9 is a view in side elevation of a modified form of the invention.

Fig. 10 is a sectional view showing a lock having a modified form of bolt and key.

Fig. 11 is detached perspective view showing the bolt and key used in the lock in Fig. 10.

Fig. 12 is a view in side elevation of a lock constructed in accordance with this invention having push button operating means on one side.

Fig. 13 is an enlarged cross sectional view substantially on broken line 13—13 of Fig. 12.

Fig. 14 is a view in longitudinal section of another modification of the invention in which the separable key is dispensed with.

Fig. 15 is a longitudinal sectional view of a window lock having push button type of operating means located in the end of the lock.

Fig. 16 is a plan view showing the form of blank from which the lock housing is made.

Referring to the accompanying drawings, throughout which like reference numerals designate like parts I have shown in Figs. 1 to 8 inclusive a window lock embodying a housing preferably formed of a single piece of sheet metal, see Fig. 16, stamped to the form shown and bent to provide a tubular guide member 17 having flange portions 18 that project sidewise and form a base therefor, and having an end portion 19 arranged at right angles to the flanges 18. The end portion 19 is preferably provided with notches 20 and the flange portions 18 are provided with tongues 21 which fit within the notches 20 and are bent downwardly to fasten the end portion 19 and flanges 18 securely together. The circular portion 22 that forms the end of the tubular guide member 17, see Fig. 16, is crimped or bent as at 23 to afford a more ornamental appearance and to form a better guide through which a key may be inserted.

When constructed as above described the

flanges 18 form a base adapted to rest upon the top rail 24 of a window sash while the end member 19 is adapted to extend downwardly over the edge of said top rail 24. 5 Screws 25 may be inserted through the flanges 18 and end portion 19 to secure the lock frame to the window sash.

Slidably disposed within the tubular guide member 17 is a bolt 26 having a pin 27 arranged to operate within a longitudinal slot 28 in the guide member 17, the pin 27 serving to limit the movement of bolt 26 in both directions. The bolt 26 is urged outwardly by a compression spring 29 that 10 abuts against the end 22 of the housing and said bolt is provided on its inner end with a shank 30 of smaller diameter having a cross pin 31 which may be engaged by a tubular key 32 for the purpose of withdrawing or retracting the bolt 26, the key 32 being provided in its forward end with bayonet slots 33 for engagement with cross pin 31. 15

The side rail 34 of the upper window sash is provided with suitable sockets into which 20 the end of the bolt 26 may project. The socket that registers with the bolt 26 when the window sash are in the closed position is preferably a short piece of metal tube 35, Figs. 4 and 8, that is inserted into a hole in 25 the upper sash bar 34 so that when the sash are closed the bolt 26 will snap into the tube 35 thereby securely locking the two sash together.

If desired a separate metal disc 36 may 30 be inserted in the hole in the sash bar 34 before the tube 35 is placed therein to prevent tampering with the window lock by 35 boring through from the outside, or the tube 35 may be provided with a solid end which 40 obviates the need of the separate metal disc 36.

For locking the window sash in an open 45 position a socket of the form shown in Fig. 7 is preferably used, said socket comprising a tubular member 37 having on its forward end an annular flange 37' arranged to be secured to the sash bar 34 by screws 38. A disc 39 slidably within the tube 36 and urged outwardly by a relatively weak compression spring 40 is adapted to close the opening at the outer end of the tube 36 except when a bolt 26 is projected into said tube 36. This type of socket being of ornamental appearance is adapted to be used in 50 places where it may be seen, the disc 39 closing the opening and serving to exclude dirt from the tube 36. One or more sockets of the form shown in Fig. 7 may be used as desired to afford various adjustments permitting a window to be locked in various 55 open positions.

When this device is locked it is practically impossible for a person on the outside of the window to tamper with and effect the release 60 of the lock. The lock being key operated

can only be unlocked by the use of a proper key and cannot be operated by the hand even though a person on the outside should be able to reach the lock through the window.

In Fig. 9 I have shown a modified form of window lock embodying a bolt housing 41 that is similar to the bolt housing previously described except that it is provided with a spiral slot 42 wherein a pin 43 on a bolt 44 is operatively disposed. Bolt 44 is urged outwardly by compression spring 45 and has squared shank 46 on its inner end that is arranged to fit within a square socket in the end of a key member 47. Bolt 44 may be retracted by inserting key 47 and turning same, pin 43 moving in spiral slot 42 when bolt 44 is turned and serving to retract or move said bolt rearwardly against the pressure of spring 45 and spring 45 serving to snap bolt 44 into a locked position as soon as key 47 is released.

Figs. 10 and 11 show a window lock similar to that shown in Figs. 1 to 8 inclusive except that a different form of key operating means is provided, said lock embodying bolt 48 having in its inner end a diametrically arranged slot 49 intersecting a transverse perforation 50 of larger dimensions than said slot. A flat key 51 having a nob 52 on one end is adapted to be inserted through the slot 49 and then turned to position the flat nob 52 substantially crosswise of the perforation 50 so that the bolt may be retracted by pulling on the key.

Figs. 12 and 13 show another modified form of the invention in which a lock housing 53 similar to the previously described lock housing is provided with a slot 54 having an enlargement 55 at one end. A bolt 56 slidable in housing 53 is provided with an indentation 57 wherein is disposed a push button 58 urged outwardly by a compression spring 59 and held by a screw 60. The push button 58 has an outer end portion 61, of smaller diameter, adapted to slide within slot 54, the larger inner end portion 58 of said push button being of suitable size to fit snugly within the enlarged end 55 of slot 54. A suitable spring, not shown, is used to urge bolt 56 outwardly as previously described. When the larger portion 58 of the push button is within the enlarged end 55 of the slot the bolt 56 will be securely held in the locked position. The bolt 56 may be retracted by first pushing inwardly on the push button and then pulling the same toward the outer end of housing 53, the smaller portion 61 of the push button moving in the slot 54.

Fig. 14 shows another alternative construction in which a bolt 62 is held in extended or locked position by a member 63 formed of a piece of spring metal bent substantially double and provided with shoul-

ders 64 arranged to lock against the end 65 of a bolt housing. The outer ends of the member 63 project through a slot 66 in the end 65 of the bolt housing and the inner end of the member 63 is secured to the bolt 62. A compression spring 67 urges the bolt 62 outwardly. The bolt 62 is retracted by pressing the ends 68 of the member 63 together and pulling outwardly on the same.

10 The spring 67 is strong enough to overcome frictional resistance of member 63 and snap bolt 62 back into a locked position after it has been retracted.

Fig. 15 shows another alternative construction in which a push button 69 in the end of a lock housing 70 is used for retracting a tubular bolt member 71. The push button is connected with lazy tong links 72 which are mounted on a pivot 73 that is connected with housing 70 and are connected at their forward end by pivot 74 with bolt 71. A spring 75 extending around pivot 73 tends to urge lazy tong links 72 into an extended position and to project bolt 71 outwardly. A relatively slight inward movement of push button 69 will produce a very much greater inward movement or retraction of bolt 71. A finger hold 76 is preferably stamped out of the end of housing 70 so that the finger may be hooked thereunder when exerting a pressure on push button 69.

In various forms of locks hereinbefore described the housings and bolt members are all of similar construction and operate in a similar manner, the bolt members being urged outwardly by suitable springs and the means for retracting the bolt members being of various different forms. The sockets shown in Figs. 7 and 8 are used in connection with all forms of locks herein shown

and described it being understood that the spring 40 in the socket shown in Fig. 7 is weak enough so that it will be compressed by the pressure of the spring in the lock and permit the bolt to enter fully and freely 45 into the socket 36.

The device is strong and simple in construction, neat and ornamental in appearance, comparatively cheap to manufacture, easy to install on windows of the usual type 50 and is especially efficient in operation said device making it possible to dispense with all other locks on the window and making it possible to lock the window firmly and securely either in a fully closed or partially 55 open position with assurance that the lock cannot be tampered with by persons on the outside of said window.

The foregoing description and accompanying drawings clearly disclose what I now regard as preferred embodiments of my invention but it will be understood that numerous changes may be resorted to within the scope of the following claim.

I claim:

65 A window lock, embodying a tubular bolt guide arranged to be secured to the top of a window sash, a bolt movable in said bolt guide, a spring urging said bolt outwardly, a spring member bent double and secured 70 to the end of said bolt, said bolt guide having an opening in one end through which the ends of said spring member project and shoulders on said spring member arranged to snap into locked engagement with the 75 end of said bolt guide and to be released by pressure on the outer ends of said spring members.

ERNEST C. KIRKPATRICK.
